UNITED STATES PATENT OFFICE.

ROBAH J. BINKLEY, OF POMONA, CALIFORNIA.

BEET-CUTTING MACHINE.

1,238,982.

Specification of Letters Patent.

Patented Sept. 4, 1917.

Application filed July 5, 1916. Serial No. 107,507.

To all whom it may concern:

Be it known that I, ROBAH J. BINKLEY, a citizen of the United States, residing at Pomona, county of Los Angeles, State of California, have invented new and useful Improvements in Beet-Cutting Machines, of which the following is a specification.

Broadly speaking this invention relates to beet cutting machines used in sugar factories for shredding beets prior to extracting the sugar therefrom. In some respects it is an improvement on my Patent 1,075,624, to which reference is made, although additional features are here shown. These machines usually comprise a revoluble member mounted in a stationary casing. The latter holds the beets, while the former is equipped with the frames that hold the cutting knives. The frames are made easily removable from the machine so that dull knives in the machine can be quickly replaced with sharp ones. This is important because the duty of these machines is heavy, and the knives dull fast, so that changes must be frequently made. Therefore each machine has a duplicate set of frames, one set operating in the machine, while the other set is being stripped of dull knives by the attendant, and equipped with sharp ones. Consequently, when the knives in the machine become dull, the machine is stopped, the frames with the dull knives are pulled out, and the one with the sharp knives are pushed in. In this way the machine need be stopped only a short time and can be quickly restarted with the sharp knives in place. The operation of the machine, and therefore of the entire factory, is thus kept practically continuous, and this continuity, in part, accounts for the high over-all mill efficiency attained in sugar factories. So far as this invention is concerned, it relates chiefly to improvements in the frames.

In my new frames the knives and guide bars can be adjusted and fastened to the frame without turning the frame over. This is more important than may at first be thought. In the form of frame previously used, the frames lie flat on the table while adjustments are being made. During this period the knives and guide bars are more or less loose so that they can be easily pushed into adjusted relation. When they are adjusted the frame is turned over, the nuts on the bottom are fastened, and by this

means the relatively loose knives and guide bars become securely bound and fastened in place. However, in turning the frames over, the loose knives and bars are sometimes jostled out of position before the fastening is accomplished. This disturbs the adjustments and destroys the uniformity of the several settings between the knives and guide bars. Of course, if the settings or adjustments are not uniform the cuttings will not be uniform. The cuttings from some knives will be thick and the cuttings from other knives will be thin. This lack of uniformity impairs the efficiency of subsequent milling operations and is deemed objectionable by practical sugar men. Strict uniformity in the thickness and character of the cuttings is what is desired. In my frames this uniformity is secured to a greater degree than in former frames. This is due largely to the fact that the knives and guide bars can be fastened and adjusted without turning the frames over, and therefore by eliminating the danger of the knives or guide bars slipping during this period, the adjustments and the cuttings are more strictly uniform. The efficiency of subsequent milling operations is slightly increased in this way, and therefore, by use of my frames, a little more sugar is recovered from the beets,—i. e. a little less goes to waste;—the quality of the sugar is slightly purer; and the costs are slightly less.

Furthermore, with the corrugated bars, I find that a particular inclination between the knife and the guiding face of the bar secures the best results. In the old method of adjusting the bars,—namely by rocking them on their concave seats, see my Patent 1,075,624, Fig. 3,—this inclination is necessarily changed every time the adjustment is changed. The ideal inclination is therefore realized only at one specific adjustment, and at all other adjustments an inferior inclination results. In my invention this is eliminated, and the ideal inclination is maintained throughout all the adjustments. The inclination does not change when the adjustment is changed, and the best inclination having been originally selected, is maintained at all times, and the best results in this respect are continually secured regardless of the adjustment.

Other advantages will appear from the specifications, and from consideration of

the drawings, but attention is called to the construction whereby wear parts are made detachable so that they can be easily replaced with little expense.

5 The figures illustrate one form of the invention.

Figure 1 is a side view showing the frame partly in section. Fig. 2 is a top view of the frame. Fig. 3 is an enlarged fragmental 10 view showing my improved means for fastening the knives to the frame. It represents a section through line X^3-X^3 , Fig. 1. Fig. 4 illustrates the cutting edge of the knife looking straight at it. Fig. 5 illustrates the 15 alined relation between the corrugations in the knives and the corrugations in the guide bars. Fig. 6 illustrates an enlargement of same. Fig. 7 shows the ideal hollow V cuttings which the corrugated guide bars 20 produce in the drum cutter. Fig. 8 shows the irregular solid cuttings produced when a flat guide bar is used instead of a corrugated one. Fig. 9 is a sectional view of the frame through line X^9-X^9 , Fig. 1, 25 omitting the knife. Figs. 10 to 17, inclusive, illustrate separately the parts shown in Fig. 9. Fig. 9 shows them assembled. Fig. 10 represents one part of the guide bar. Fig. 11 represents another part of the guide bar. Fig. 12 is a top view of the member shown 30 in Fig. 11. Fig. 13 is a top view of the fastening wedge. Fig. 14 is a side view of this wedge. Fig. 15 is an end view of same. Fig. 16 is a side view of the raising and lowering wedge. Fig. 17 is a top view of same. 35

Referring to Figs. 1 and 2 the frame proper is shown at 1. This is more or less of a skeleton member through which the shreds pass freely when cut, and to which 40 the knives, guide bars, and operating parts, are fastened. The frame comprises the side parts 2, and the cross bars 3, the latter also serving as supports to which the knives and guide bars are fastened. Each frame has 45 three cross bars 3, one underlying each of the three sets of knives with which the frame is equipped. The side walls 2 of the frame are cast integrally with the cross bars 3, and these two parts, namely the sides and 50 cross bars, practically constitute the entire frame.

The knives are indicated at 4, and the guide bars at 5. There are three sets of knives and guide bars in each frame. Each 55 set comprises one bar 5, and two knives 4. Two of the sets are shown in Fig. 2, the third set, namely the right hand set, being omitted so as to more clearly show the parts below. The two knives in each set lie side 60 by side, each knife engaging only one half of the adjacent guide bar. The chief reason for having the two knives instead of one wide one extending across the entire bar, is that the knives sometimes break, and it is 65 often necessary to discard only one of these

narrow knives, instead of both of them, as would virtually be the case if they were made in one. The cutting edge 6 of the knife is corrugated and the corrugations run back along the knife as indicated at 7. 70 This is best understood from Figs. 1 and 2, particularly in connection with Fig. 4 which shows the cutting edge looking straight at it. The guide bars are also corrugated with similar corrugations 8. As illustrated in 75 Figs. 5 and 6, particularly the latter, these corrugations in the knives register accurately with the corrugations in the guide bars, and as a result the shreds cut from the beets are hollow V in section as shown in 80 Fig. 7. If the guide bars were flat instead of corrugated, as was the case, at least in drum cutters, before my invention covered by Patent 1,075,624, the cuttings come out irregular and more solid as indicated in Fig. 85 8. The object in the sugar business however, is to get cuttings of the form shown in Fig. 7, and to get them as nearly absolutely uniform as possible. It is in this respect that this invention accomplishes a very notable advance by making it easy, in fact routine, to get shreds of absolutely uniform thickness, and, if the corrugated guide bar is used, at 90 least in the drum cutter, to get all the shreds perfect in V section as shown in 95 Fig. 7.

One feature that contributes to this largely is the manner in which the knives and guide bars are fastened to the frame. Fig. 3 in my Patent 1,075,624 shows the old 100 way. These specifications disclose the new way.

The means by which I fasten the knife is shown in Figs. 1, 2, and 3. As shown the knife is equipped with two converging channels 9 at the rear, these channels being narrower at the bottom than at the top so as to firmly seat washers 10, see Fig. 3. These washers, being elongated, are strong in themselves, and also have a very effective 110 frictional engagement in channels 9 for firmly holding the knife. A bolt 11, having a slotted head 12, passes through washer 10. This head is also conical in shape so as to effectively engage the washer, see Fig. 3. Bolt 11 passes loosely through elongated slot 13 in cross bar 3 of the frame, see particularly Fig. 2, right hand side, and below this engages a nut 14 in the cavity 15 of the cross bar. 115

To remove the knives from the frame it is only necessary to loosen bolt 11. This may be done with an ordinary screw driver if the attendant is not equipped with my special tools, and after loosening the bolt 125 a little, the front edge 6 of the knife, Fig. 1, can be raised so as to clear the guide bar 5, and the knife can then be drawn out from under the washers 10 and removed from the frame. For this purpose bolt 11 130

need be loosened only a little, and should not be loosened so much as to disengage nut 14. The bolt is made long enough to allow ample clearance for removing the 5 knife without disengaging the nut. However, if the attendant does disengage the nut it matters only slightly. Nut 14 will drop onto base 16 of cavity 15, and will ordinarily stay there. To reengage the nut, 10 the attendant need merely screw up on the bolt just as though the nut were engaged, and in view of the tapered relation between the bottom 17 of the bolt, and the top 18 of the nut, these two members will automatically 15 find and engage each other. However, if difficulty is encountered, the nut can be reset with the fingers in the ordinary manner, but this troublesome situation should be rarely experienced. The next 20 point that should be noticed is the relation between rear wall 19, of cavity 15, slot 13, and nut 14, which is such that wall 19 normally engages nut 14, and prevents the latter from turning when the bolt is screwed 25 through it. This is just as effective as if a wrench were holding the nut, and permits the entire fastening to be effected by merely turning the bolt. This can be effected entirely 30 from the top of the frame and its convenience is manifest. In addition, as previously indicated the frame need not be turned over, and this aids in the accuracy and uniformity of the setting.

Before concluding the description of the 35 fastening means for the knife, attention is called to the relation between the converging channels 9 in the rear of the knife, and the elongated slots 13, in the frame, running crosswise of the channels, see Fig. 2. 40 In view of the converging relation between the channels, and the frictional resistance of nut 14 against side motion of bolt 11, the construction shown represents a very efficient fastening means which not only has the common fastening features but also has 45 a toggle or locking effect between the knives and the bolts, so that the knives cannot slip even slightly in any direction, and of course cannot rise off the frame. This locking 50 effect is quite helpful.

We now come to the means for fastening and adjusting the guide bars.

The best assembly view of this means is shown in Fig. 9. Also, see the sectional 55 portion of Fig. 2. The separate elements comprising this means are shown in Figs. 10 to 17 inclusive.

In order to illuminate the assembly views, the element shown in Fig. 10 is designated 60 by reference character "a"; the element in Figs. 11 and 12 by "b"; the element in Figs. 13, 14, and 15, by reference character "c"; and the element in Figs. 16 and 17 by "d".

65 The guide bar proper includes elements

a and b. In practice these two elements are securely joined to each other, and work and behave as though they were one. I have shown them disjoined only because I deem it advisable to build element a separate from 70 element b. When the corrugations in a are worn, this member can be replaced with but slight expense, and member b need not be replaced also. Member b is more complicated and expensive than member a, and 75 can outlive several of the bars a, which is desirable and indicates the advantage sought. From a structural standpoint these elements should be treated as one. a is attached to b by common screws which engage the threaded apertures 20 in the bar a, see Fig. 10. These screws come up through apertures 20' in element b. The screws, being of ordinary form, are however omitted for purposes of clearness. 80 Member b, see Fig. 11, has a flat upper face for receiving and securely holding member a. Member b also has two inclined planes 22 which engage similar inclined planes 23 on lifting wedge d, see Fig. 16. 90 In addition, member b also has an inclined plane 24, engaging a similar inclined plane 25 on the fastening wedge e, see Fig. 15. The relative position of the fastening wedge on member b is indicated by dotted lines in 95 Fig. 12.

Figs. 16 and 17 illustrate the lifting wedge d. To understand the operation of this member, and its coöperation with members a and b, reference should be made to 100 Figs. 1, 2, and 9, where these members are shown in assembled relation. They are assembled in a suitable recess or cavity 25', Fig. 2, in the frame. This cavity is formed in cross bar 3 specially for this purpose. 105 Ledge 26, Figs. 1 and 2, represents the bottom portion of this recess, whereas 27 is the rear wall, and 28 the front wall, see particularly Fig. 1. The lifting wedge d rests on the bottom 26 of the cavity, and is short 110 enough to have a suitable sliding motion lengthwise therein. Members a and b on the other hand rest on the wedge member d, and span the cavity 25' throughout its entire length. 115

The lifting wedge d is moved back and forth between the bottom ledge 26 and the guide bar members a and b, by means of an adjusting bolt 29, see Figs. 1 and 2, which has a screw connection with the female threaded portion 30 of the wedge d, 120 Figs. 16 and 17. The head 31 of this bolt is formed so as to engage an ordinary wrench, and the entire head is countersunk into the wall 2 of the frame, see Figs. 2 125 and 9, so as to leave the frame smooth on the side. This bolt is adapted to push the wedge as well as pull it, and this is accomplished by means of the annular shoulder 32 on the bolt, which engages the body of 130

the frame on one side, and engages cap 33 on the other side. Cap 33 is fastened to the frame by means of small screws 34.

By operating bolt 29 wedge member *d* 5 is drawn back and forth, and guide bar members *a* and *b* are raised and lowered in view of the coaction between inclined planes 22 and 23. This raising and lowering is 10 very important because it is the means of adjusting the guide bar with respect to the knife. By reference to Fig. 6 for instance, it will be seen that as bar 5 is raised or lowered, the slit 35 between the bar and knife is closed or opened, and conversely as 15 the width of this slit is changed, the thickness of the cuttings, see Fig. 6, is also changed. These shreds should be thicker or thinner according to the particular quality of beets passing through the mill at any 20 particular time, because the efficiency of the osmotic forces of abstraction, and other forces, in the subsequent stages of the sugar abstraction, varies not only with the thickness but also with the quality of the beets. 25 Therefore, as the quality changes from time to time,—*i. e.* as to sugar content, and other chemical features,—the thickness of the cuttings must be correspondingly changed in order to maintain the highest efficiency of 30 abstraction at all times. Since the quality of the beets changes quite frequently, this adjustment must also be changed frequently, and therefore it is of the utmost importance that it be easily and quickly effected. My 35 construction accomplishes this very nicely, but before reviewing the operation in detail, I desire to describe the means for fastening the guide bar members *a* and *b* to the frame so that they will not fall out or 40 become disarranged when the frame is inverted during the operation of the machine. Figs. 13, 14 and 15 show one means which I propose for this purpose.

These figures illustrate the wedge *c* which 45 comprises the base 36 and the upstanding forked portion including the two arms 37. These arms reach around shank portion 38 of member *b*, so as to effect an engagement between inclined planes 25 of wedge *c*, and 50 inclined plane 24 of member *b*. When the parts are in place in the frame the arms 37 reach up through the bottom 26 of the frame through a suitable channel 38, see Fig. 2, therein, which may extend clear 55 across the frame or only part way across as indicated. The base 36 of wedge *c* engages the lower face of bottom portion 26 of the frame, see Fig. 1, and by virtue of 60 the support thus given to the wedge, against upward thrusts, the arms 37 are able to vigorously engage wedge 24 of member *b* and securely bind and fasten this member to the frame.

Wedge *c* is also prevented from falling 65 down through the frame, not only by virtue

of its arms 37 which rest on wedge 24, of member *b*, but also by means of beveled sides 39, of its base portion 36, see Figs. 1 and 15, which engage the similarly beveled plates 40, Fig. 1, fastened to the frame.

70

In order to manipulate wedge *c* back and forth so as to permit it to engage wedge 24, in member *b*, in the various positions assumed by the latter, I provide bolt 41, see Fig. 2, which engages the threaded female portion 42 of wedge *c*, see Figs. 14 and 15. This bolt is adapted to push and pull wedge *c* in the same manner that bolt 29 pushes and pulls wedge *d*, and for this purpose the construction of bolt 41, and its engagement with the walls of the frame, are identical with that of bolt 29, so that the description of the latter, will also serve for the former.

75

With the exception of a few details this now completes the description of my frame 85 and its connected parts, and no doubt many of its advantages will be clear from remarks already made. In conclusion however, it may be stated that the particular form of frame shown is that which serves the drum 90 cutters. This is indicated by the arc of the frame in Fig. 1. In drum cutters there are usually eight such frames in a set, and when they are arranged in the machine they practically form a continuous circle or 95 drum with the knives and guide bars alternately arranged around the internal periphery thereof. The general construction of such machines is old and well known, and need not be here described in detail, but for 100 purposes of reference it may be remarked that the general construction of such a machine is shown in Figs. 1 and 2 of my Patent 1,075,624, to which attention has already been called. During operation the 105 beets are loaded into the drum formed by the chain of frames, and the beets are held fast against rotation by some suitable stationary apron, while the frames, constituting the drum, are revolved past the beets 110 by suitable motive power applied to the machine. In view of the force with which the beets are fed into the drum, and also of the peculiar wedging action incident to the shape of the drum, the beets press down 115 firmly onto the revolving knives and guide bars carried around by the frames, and the result is that long shreds having the V section shown in Fig. 7, are cut from the beets, and come out through channel 43 in the 120 frame, passing away in direction of arrow *e*, Fig. 1. Arrow *f* indicates the direction of revolution of the frame when arranged in the machine.

125

After one set of frames has been operating a while, the knives become dull. The frames are then withdrawn from the machine and bolts 11 are loosened. The old knives are taken out and new sharp ones are put in place. Before fastening the new knives in 130

place however, they must be adjusted so that the width of slot 44, between the knives and guide bar, see Figs. 1 and 2, is correct in the judgment of the operator. This adjustment between the knives and guide bar is made by shifting the knife back and forth in the direction of arrow f' , Fig. 2, such shifting being possible in view of the sliding engagement which the bolts 11 have, when loose, through channels 9 of the knives and slots 13 of the frames. This ability to adjust the knives back and forth is also important because, in view of the knives being sharpened from time to time, they rapidly become short, and must be shoved up toward the guide bar in order to maintain the correct width of slit 44, between the knife and guide bar. However, after the knives are adjusted and fastened so as to comply with the foregoing conditions, the operator next turns his attention to the adjustment of the guide bar. This bar is adjusted as to height so as to make the slit 35, Fig. 6, between the top of the guide bar and the knife, correct. As previously indicated this slit controls the thickness of the cuttings, and it must be varied from time to time in order to suit the quality of beets passing through the mill. This adjustment is made, first by operating bolt 41 so as to back the fastening wedge c off of wedge 24 of member b , so as to liberate member b and allow it to move up and down. By means of bolt 29, wedge d is then operated back or forth, and the guide bar members a and b , also designated by reference numeral 5, are raised or lowered to the particular height required. When the correct height is attained the fastening wedge c is again drawn into position by means of bolt 41, and the guide bar parts a and b are firmly fastened to the frame in their new adjusted positions. When this is done the setting of the knives and guide bars is complete, and the frame is ready to be put back into the machine as soon as the next change of frames is called for.

By comparing this method of setting the knives and bars, with the method formerly required, it will be noticed that with my frames all changes and adjustments of the knives and guide bars can be made from the top or side of the frame, so that the frame can remain flat on the table, and need not be raised or turned over, and need not be disturbed in any other way, in order to accomplish the results sought. Neither the knives nor the guide bars are fastened from below. Consequently after these members have been pushed into adjusted relation and are still loose, they can be easily and immediately fastened in place without disturbing the frames, and all danger is therefore eliminated of these parts being jostled out of adjustment before the fastening is

accomplished. As compared with former methods, where the frames had to be turned over in order to fasten the knives and bars, my construction achieves a considerable improvement by insuring more accurate and uniform adjustments, and this result evidences itself by substantial savings in various parts of the mill.

The next feature that should be observed is the manner in which the inclination or angular relation between the top guiding face of the bar and the knife is kept constant throughout all adjustments. This is best seen from Fig. 1, where the greater part 46 of the bar is seen to have a slight inclination with the plane of the knife. The amount of this inclination is important because it governs the amount of the corrugations of the bar which catch in the corrugations of the beets, and this latter factor controls the effectiveness of the corrugated guide bar in accurately guiding the corrugations of the beet into the corresponding corrugations of the next knife so as to insure the uniform cutting of V shaped corrugations of the form shown in Fig. 7. Now the adjustment of my bar is accomplished by raising it straight up and down, and not by tilting it in either direction, as is customary in other frames, and in this way the inclination of my bar never changes but remains constant for all adjustments. I gage this inclination scientifically in the first instance, so as to secure the best results, and this inclination remaining constant at all times, these results are uniformly maintained regardless of changes of adjustment. Obviously this is another important advantage.

The following feature is somewhat in the same strain. By referring to Figs. 11 and 12, also, Figs. 16 and 17, it will be seen that the inclined planes 22 and 23 are disposed on each side of both the long and short axis, so to speak, of member b , viewing this member in the direction shown in Fig. 12. In this way the member is firmly supported on these planes, and when it is raised or lowered these supports tend to raise or lower it uniformly, and there is no tilting action in any direction. Also, by having the slot 50 in member d , see Fig. 17, room is made for the fastening wedge c , and by having this wedge perform its locking or fastening function between the inclined planes 22 and 23, this wedge also promotes the spirit of solidarity and levelness in the foundation for the bar.

Of course many of the features hereinbefore brought out may be varied extensively, without departing from my invention, and in this connection I wish to emphasize that this disclosure, and the accompanying drawings, point out only one form in which the invention may be employed. The scope of

the invention is indicated only by the limitations in the appended claims.

As a final remark concerning details, attention might be called to wear strip 48. 5 The inner top corner and sides 47, see Figs. 2 and 9, of the frame, wear rather fast in view of the continuous drag of the beets at this point. After this wear has progressed to a certain point it somewhat impairs the 10 cutting action of the knives at these sides. Therefore, in order to easily eliminate this, I provide the removable wear strips 48 which are fastened to sides 2 of the frame by screws 49 indicated in Fig. 2. When these 15 strips become worn they can be easily and quickly replaced with new ones.

Claims:

1. In combination, a removable frame for beet cutting machines, a beet knife fastened 20 to said frame, a guide bar mounted in said frame adjacent the knife, the guiding face of the bar having a definite relation with respect to the plane of the knife, means for raising and lowering the guide bar up and 25 down evenly so as to effect an adjustment between the bar and knife without changing the said relation between the guiding face of the bar and the knife, and means for fastening the bar to the frame.

2. In combination a removable frame for beet cutting machines, a beet knife fastened to said frame, a guide bar mounted in said frame adjacent the knife, the guiding face of said guide bar having a definite relation 35 with respect to the plane of the knife, wedge means for raising and lowering said guide bar up and down evenly so as to effect an adjustment between the bar and knife without changing the said relation between them, 40 and means for fastening the said guide bar to the frame.

3. In combination a removable frame for beet cutting machines, a beet knife fastened thereto, a guide bar mounted in said frame 45 adjacent the knife, a wedge for raising and lowering the guide bar evenly without tilting the guide bar with respect to the knife, said wedge having a slot therein and means passing through said slot for fastening said guide bar to the frame.

4. In combination, a removable frame for beet cutting machines, a beet knife fastened to said frame, a guide bar mounted in said frame adjacent the knife, the guiding face 55 of the bar having a definite angular relation with the plane of the knife, means for raising and lowering the guide bar so as to effect an adjustment between the bar and the knife without changing the angular relation 60 between the guiding face of the bar and the knife, and means for fastening the bar to the frame the last said means including a wedge.

5. In combination, a removable frame for beet cutting machines, the surface of said

frame following substantially the arc of a cylinder, a corrugated beet knife fastened to said frame on the internal periphery of said cylindrical arc, a corrugated guide bar adjacent the knife and also mounted on the 70 internal periphery of the frame, the corrugations in the guide bar being alined so as to register with the corrugations in the knife and the guiding face of the bar having a definite angular relation with the plane of 75 the knife, and means for raising and lowering the corrugated face of the guide bar evenly up and down so as to effect an adjustment between it and the knife without changing the said angular relation between 80 the guiding face of the bar and the plane of the knife.

6. In combination, a removable frame for beet cutting machines, a beet knife fastened to said frame, a guide bar connected to said frame, said guide bar being adapted to be adjusted as to height relative to said knife, and means for so adjusting said bar, said means including a wedge, and a screw operated from the side of the frame for operating the wedge.

7. In combination, a removable frame for beet cutting machines, a beet knife fastened to said frame, an elongated guide bar connected to said frame, said guide bar being 95 adapted to be adjusted as to height with respect to said knife, and means for so adjusting said bar, said means including a wedge and a screw for said wedge, said screw being adapted to normally operate and draw 100 the wedge in a direction substantially parallel to the long axis of the elongated guide bar.

8. In combination, a removable frame for beet cutting machines, a beet knife fastened 105 to said frame, an elongated guide bar connected to said frame, said guide bar having a plurality of inclined planes, one of said inclined planes being on one side of the short axis of said elongated bar, and another 110 of said inclined planes being on the other side of said short axis of the bar, and wedge means for raising and lowering said bar so as to effect an adjustment between the said bar and knife, said wedge means also having a plurality of inclined planes corresponding to and engaging the said inclined planes of the guide bar so as to prevent any tilting of the guide bar about its short axis as the guide bar is raised or lowered by the 115 said wedge means.

9. In combination, a removable frame for beet cutting machines, a beet knife fastened to said frame, an elongated guide bar connected to said frame, said guide bar having a plurality of inclined planes, one of said inclined planes being on one side of the short axis of the bar and another of said inclined planes being on the other side of said short axis of the bar, said inclined planes also 120

- being disposed on both sides of the long axis of said bar, and wedge means for raising and lowering the bar, said wedge means also having a plurality of inclined planes corresponding to and engaging the inclined planes of the bar, said wedge means being thereby adapted to raise and lower said elongated guide bar without tilting the latter either about its long or short axis.
10. In combination, a removable frame for beet cutting machines, a beet knife fastened to said frame, an elongated guide bar connected to said frame, said guide bar having a plurality of inclined planes, one of said inclined planes being on one side of the short axis of the elongated bar, and another of said inclined planes being on the other side of said short axis of the bar, wedge means for raising and lowering the guide bar, said wedge means including a plurality of inclined planes corresponding to and engaging the said inclined planes of the bar, and means for fastening the guide bar to the frame between the said inclined planes of the bar.
11. In combination, a removable frame for beet cutting machines, a beet knife fastened to said frame, an elongated guide bar fastened to said frame, said guide bar having a plurality of inclined planes, one of said inclined planes being on one side of the short axis of the bar, and another of said inclined planes being on the other side of said short axis of the bar, wedge means for raising and lowering the guide bar, said wedge means including a plurality of inclined planes corresponding to and engaging the above mentioned inclined planes on the bar, and wedge means having an engagement with the frame for fastening the guide bar to the frame, the last mentioned wedge means operating between the above mentioned inclined planes on the bar.
12. In combination, a removable frame for beet cutting machines, a beet knife fastened to said frame, an elongated guide bar adapted to be adjusted as to height with respect to said frame, means for so adjusting the bar, said means including a wedge, a screw for operating said wedge, said screw being adapted to normally operate and draw said wedge in a direction substantially parallel to the long axis of the guide bar, means for fastening the guide bar to the frame, said last mentioned means including a wedge, and a screw for operating the last said wedge, the last said screw being adapted to operate its wedge in a direction substantially parallel to the direction of operation of the first said wedge.
13. In combination, a removable frame for beet cutting machines, a beet knife fastened to said frame, an elongated guide bar adapted to be raised and lowered so as to effect an adjustment between said bar and knife,
- means for raising and lowering the bar, said means including a lifting wedge, a screw for operating the lifting wedge, said screw being adapted to normally operate and draw said wedge in a direction substantially parallel to the long axis of said bar, means for fastening the guide bar to the frame, said last mentioned means including a fastening wedge, and a screw for operating the fastening wedge, the last mentioned screw being adapted to normally operate its wedge in a direction substantially parallel to the direction of operation of the first said wedge, the screw for the lifting wedge and the screw for the fastening wedge being respectively located and operated from opposite sides of the frame.
14. In combination, a removable frame for beet cutting machines, a beet knife fastened to said frame, a guide bar for said knife connected to said frame, a lifting wedge for said bar adapted to raise and lower said bar so as to effect an adjustment between the bar and the knife, and a fastening wedge for fastening the bar to the frame.
15. In combination, a removable frame for beet cutting machines, a beet knife fastened to said frame, a guide bar for said knife connected to said frame, a lifting wedge for said bar adapted to raise and lower said bar so as to effect an adjustment between it and the knife, said lifting wedge having an inclined plane, a fastening wedge for fastening the bar to the frame, said fastening wedge having an inclined plane, the said guide bar also having inclined planes adapted to engage and coöperate with the said inclined planes on the lifting wedge and on the fastening wedge.
16. In combination, a removable frame for beet cutting machines, a beet knife fastened to said frame, a guide bar for said knife, said guide bar being connected to said frame, a lifting wedge for said bar adapted to raise and lower said bar so as to effect an adjustment between the bar and knife, said lifting wedge having an inclined plane, a fastening wedge for fastening said bar to the frame, said fastening wedge having an engagement with the frame, said fastening wedge also having an inclined plane, inclined planes on the said guide bar adapted to engage and coöperate with the said inclined planes on the lifting wedge and on the fastening wedge, and screw means manipulated from the side of the frame for operating the said lifting wedge and the fastening wedge.
17. In combination, a removable frame for beet cutting machines, a beet knife fastened to said frame, a guide bar for said knife, said guide bar being connected to said frame and having two inclined planes for lifting and lowering the bar, another in-

clined plane on the bar between the first two inclined planes, a lifting wedge having inclined planes coöoperating with the first two inclined planes of the bar for raising 5 and lowering the bar to effect an adjustment with the knife, a fastening wedge having an inclined plane coöoperating with the third inclined plane on the bar for fastening the bar to the frame, and screw means operated 10 from the side of the frame for operating the said lifting wedge and the said fastening wedge.

18. In combination, a removable frame for beet cutting machines, a beet knife 15 connected to said frame, a guide bar for said knife, said guide bar also being connected to said knife, said guide bar having two inclined planes for lifting and lowering the bar, said bar also having a relatively narrow 20 shank portion and a third inclined plane between the first two inclined planes, a lifting wedge with an elongated slot running lengthwise thereof, said lifting wedge

having two inclined planes for engaging the first two inclined planes of the guide bar 25 for raising and lowering the bar to effect an adjustment between it and the knife, a fastening wedge having an engagement with the frame and extending through said elongated slot in the lifting wedge, said fastening wedge also having two arms with an inclined plane therein, said arms being adapted to reach around the narrow shank portion of the guide bar so as to bring the inclined plane on the arms of the fastening 30 wedge into engagement with the third mentioned inclined plane of the guide bar, and screw means manipulated from the side of the frame for operating said lifting wedge and said fastening wedge. 40

In testimony whereof, I have hereunto set my hand at Los Angeles, county of Los Angeles, State of California, this 20th day of June, 1916.

ROBAH J. BINKLEY.
